WINDOW CONSTRUCTION

Karl Puidak, Kansas City, Mo.

Application November 13, 1957, Serial No. 696,202

9 Claims. (Cl. 20—53)

This invention relates to improvements in window construction, and more particularly to a structure wherein the window sash is secured in sealed relationship to the window frame defining the window opening.

The principal objects of the present invention are to provide a window construction wherein the window sash is bodily movable relative to the window frame or casing and is held in sealing engagement with magnetic securing devices; to provide a window structure wherein the sash is bodily movable for maximum ventilation with cooperative sealing members on the sash and frame held in weathertight engagement with permanent magnets removably mounted on the sash and cooperating with pole plates on the window frame; to provide magnet housings having through passages from end to end fixed on a window member with spaced side plates of mild steel or other permeable material on each side of the passage for engagement with pole plates fixed on the window frame with bar magnets slidably and removably mounted between the side plates of the housing whereby the magnetic flux is increased to securely hold the window member relative to the frame; to provide such a structure wherein the mild steel side plates are mounted on the window member whereby the side plates are engaged with non-magnetic material of the window member or mounting; to provide such a window construction in which the individual magnets may be easily removed from their respective housings to release the window relative to the frame and yet have a structure wherein the magnets when in place with increased magnetic flux provided by the mild steel side plates will hold the windows with a very strong force that will resist high winds and the like; and to provide a window construction that is economical to manufacture for positively securing window sash relative to the window jambs yet be readily removable with a minimum of effort.

In accomplishing these and other objects of the present invention, I have provided improved details of structure, the preferred forms of which are illustrated in the accompanying drawings, wherein:

Fig. 1 is an elevational view of a window construction held in closing position.

Fig. 2 is an enlarged fragmentary perspective view of the window frame, window sash and seal frame with the securing members thereon in disassembled relation.

Fig. 3 is an enlarged fragmentary horizontal sectional view through the window construction on the line 3—3, Fig. 1.

Fig. 4 is a vertical sectional view through the window construction on the line 4—4, Fig. 3.

Fig. 5 is a vertical sectional view through the window construction on the line 5—5, Fig. 3.

Fig. 6 is an enlarged horizontal sectional view through the window construction on the line 6—6, Fig. 1.

Fig. 7 is a fragmentary perspective view of a modified form of window construction with the parts in spaced disassembled relation.

Fig. 8 is an enlarged horizontal sectional view through

2

the modified form of window construction showing the mounting of the magnetic securing members thereon.

Referring more in detail to the drawings:

1 designates a window construction comprising a window casing or frame 2 including a sill 3, side jambs 4 and a header 5, each of which is arranged to provide a blind stop 6 defining the window opening 7 and having an inwardly facing shoulder 8. In this form of the invention, the window opening 7 is relatively large and is adapted to be closed by a single sash 9 which due to the size would be inconvenient to bodily move to and from the window opening. Therefore, it is preferable that the window sash be pivotally mounted in the window opening.

15 The window sash 9 includes a frame 10 in which a pane 11 is mounted in a conventional manner, said frame having inner and outer faces 12 and 13. The sash frame is of such a size that the outer surfaces or edges 14 are slightly spaced as at 15 from the inner edges 16 of the stops 6 whereby the sash frame is movable through the window opening 7. The sash frame is pivotally mounted on trunnion members 17 rotatably supported in brackets 18 suitably secured by fastening devices such as screws 19 to the window frame, as illustrated in Fig. 6. Seal strips 20 are secured to the inner and outer faces 12 and 13 of the sash frame adjacent the periphery thereof whereby the sash is reversible in the window frame, if desired, said sash being freely pivotable in the window opening. In order to secure the sash in weathertight relation to the frame, an auxiliary frame 21 is mounted in the window frame in sealing engagement with the seal strip 20 on the inner face of the window sash, and also in sealing engagement with a resilient seal strip 22 on the face 8 of the stop 6 adjacent the inner edges thereof around the window opening.

35 The frame 21 has a peripheral wall 23 with an edge 24 adapted to engage the seal strip 22 when the wall 23 is in position surrounding the window sash frame. The edge of the wall 23 opposite the edge 24 is turned inwardly whereby the auxiliary frame is substantially L-shaped in cross section with the inner wall 25 terminating in a lip 26 adapted to engage the seal strip 20 around the inner face of the window sash frame, the auxiliary frame being such and related to the seal strips 20 and 22 whereby there is a weathertight seal completely surrounding the window sash and window opening.

The auxiliary frame is held in place to provide the weathertight seal for the window opening by means of a plurality of magnetic securing devices 27. The securing devices 27 each include housings 28 having laterally spaced side plates 29 and 30 of mild steel or other permeable material. The plates 29 and 30 are supported by non-magnetic material which in the illustrated structure is in the form of spacers 31 therebetween whereby the spacers 31 and plates 29 and 30 form through passages 32 to slidably mount bar type permanent magnets 33. The housings are positioned whereby the passages 32 are perpendicular to the face 8 of the blind stop 6, said housings preferably being mounted on the frame 21 by means of suitable fastening devices such as bolts 34 of non-ferrous metal with a spacer strip 35 of non-magnetic material between the plate 30 and the peripheral wall 23 of the frame 21 whereby the side plate adjacent said frame 21 does not contact any permeable metal. The housings are fixed on the auxiliary frame 21 at suitable spaced intervals thereon, and in the form illustrated in Fig. 1 there are eight such housings arranged around the frame. A plurality of mild steel plates 36 are fixed on the face 8 of the blind stop 6 and positioned whereby one registers with the passage of each of the housings and serves as an armature plate 36 in the magnetic securing device. The armature plates 36 are preferably

secured to the window frame or blind stop by means of suitable fastening devices 37 such as screws and the like.

When the frame 21 is positioned surrounding the window sash with the edge 24 and lip 26 sealingly engaging the sealing strips 22 and 20 respectively, the end edges 38 of the side plates 29 and 30 engage the front face 39 of the respective armature plate 36. The bar type magnets 33 each have a size to substantially fill the passage in the respective housing and engage the side plates and are slidably moved into the passages until the inner ends 40 of the magnets engage stops 41 which provide for a slight spacing between the inner ends 40 of the magnet and the armature plate 38. In the illustrated structure, the stop 41 is in the form of a non-ferrous pin extending across the inner end of the passage 32. The magnets 33 are preferably formed of sintered material sometimes referred to as ceramic magnets or other relatively strong permanent magnet of small size. When positioned between the side plates 29 and 30 and spaced slightly from the armature plate 38, the magnetic flux is materially increased providing a very strong attraction to firmly hold the auxiliary frame 21 relative to the window frame or casing. When it is desired to open the window, the individual magnets 33 may be pulled from the housings with little effort which is a mere fraction of the force holding the housings relative to the armature plate, and when the magnets are removed from the individual housings, the auxiliary frame may be lifted and removed from the window casing freeing the window sash for pivotal movement as desired. With the sealing strips 20 on the opposite faces of the sash frame, the sash may be reversed and the auxiliary frame positioned and the magnets inserted to provide a weathertight seal for the window opening and sash, positively holding the window sash in position.

In the form of the invention illustrated in Figs. 7 and 8, the window opening 44 defined by the casing 45 and blind stop 46 thereof is sufficiently small whereby the sash and frame 47 may be easily lifted and moved. In this form of the invention, the inner face 48 of the stop 46 has a seal strip 49 around the edge of the window opening and there are a plurality of spaced armature plates 50 secured to the face 48 of the stop and spaced around the window opening for alignment with passages 51 through magnet housings 52 secured to the sash frame 47.

In the modified form of the invention, the sash frame is larger than the window opening 44 whereby the frame overlies seal strips 49, the sash frame preferably having ribs 53 extending from the inner and outer faces 54 and 55 of said frame to sealingly engage the strips 49 on the stop 46. While the structure shown in Figs. 7 and 8 is such that the sash is bodily removable from the casing, it is to be understood that it could be supported for swinging movement relative thereto or other bodily movement relative to the window opening. In the structure illustrated, the sash frame 47 is formed of wood or other non-magnetic material whereby the housings 52 may be secured thereto with one side plate 56 engaging the wood portion of said sash frame. If the sash frame is made of metal, then the plate 56 should be spaced therefrom by a suitable spacer of non-magnetic material. The plate 56 is supported in spaced relation to the other side plate 57 by means of spacers 58 of non-magnetic material to form the housings 52. The housings 52 are suitably secured to the sash frame by fastening devices such as screws 59 of non-ferrous metal which extend through aligned holes in the non-magnetic spacers 58 and plates 56 and 57. The magnets 60 are insertable in the passages of the housings in sliding engagement with the plates 56 and 57 with the inner edges 61 of the magnets engaging a stop such as a pin 62 of non-magnetic material mounted in the respective plates 56 and 57 and extending across the passage therebetween whereby the end 61 of the magnet is slightly spaced from the

respective armature plate 50 mounted on the blind stop 46. When the magnets are removed from the respective housings, the sash may be bodily removed from the closing position relative to the window opening. When it is desired to close the window, the sash is moved into position with the ribs 53 engaging the seal strip 49 and with the passages 51 of the housings 52 registering with the armature plates 50 and the magnets are then slipped into the passage of the respective housing until the ends 61 engage the stops 62 at which position the magnetic flux is increased whereby the magnets firmly hold the sash in place.

It is to be understood that while I have illustrated and described one form of my invention, it is not to be limited to the specific form or arrangement of parts herein described and shown except insofar as such limitations are included in the claims.

What I claim and desire to secure by Letters Patent is:

1. A window construction of the character described comprising, a window casing, a stop extending around the window casing and defining a window opening, a window sash having a frame bodily movable relative the window opening, a plurality of permanent bar magnets, a plurality of armature plates fixed to the window casing around the window opening, a pair of laterally spaced mild steel plates for each magnet, non-magnetic members supporting the plates in spaced relation in a unit forming an open ended housing having a passage between the side plates whereby the magnets are removably and slidably positioned in the passages and sandwiched between the respective pairs of plates, means fixing the side plate units relative to the window sash with open ends of the passages between the side plates registering with the respective armature plates with the adjacent ends of the side plates engaging said armature plates when the window sash is in closing position relative the window opening, and stop means extending into the passages between the side plate adjacent the armature plates and engageable by the adjacent ends of the respective magnets to retain same slightly spaced from the armature plates whereby the magnets retain the sash in place until the magnets are removed.
2. A window construction of the character described comprising, a window casing, a stop extending around the window casing and defining a window opening, a window sash having a frame bodily movable relative the window opening, a resilient seal strip on one of the stop and window sash, cooperative structure associated with the other of the stop and window sash for engaging said resilient strip to form a weathertight seal therewith, a plurality of permanent bar magnets, a plurality of armature plates fixed to the window casing around the window opening, a pair of laterally spaced mild steel plates for each magnet, non-magnetic members supporting the plates in spaced relation in a unit forming an open ended housing having a passage between the side plates whereby the magnets are removably and slidably positioned in the passages and sandwiched between the respective pairs of plates, means fixing the side plate units relative to the window sash with open ends of the passages between the side plates registering with the respective armature plates with the adjacent ends of the side plates engaging said armature plates when the window sash is in closing position relative the window opening, and stop means fixed relative the side plate units adjacent the armature plates and engageable with the adjacent ends of the respective magnets to retain same slightly spaced from the armature plates whereby the magnets retain the sash in place until the magnets are removed.
3. A window construction of the character described comprising, a window casing, a stop extending around the window casing and defining a window opening, a window sash having a frame bodily movable relative the window opening, a removable frame associated with the window sash, a plurality of permanent bar magnets, a plurality

of armature plates fixed to the window casing around the window opening, a pair of laterally spaced mild steel plates for each magnet, non-magnetic members supporting the plates in spaced relation in a unit forming an open ended housing having a passage between the side plates with a cross section substantially corresponding to the cross-sectional shape and size of the respective magnets whereby the magnets are removably and slidably positioned and sandwiched between the respective pairs of plates, means fixing the side plate units relative to the removable frame with the open ends of the passages between the side plates registering with the respective armature plates with the adjacent ends of the side plates engaging said armature plates when the window sash is in closing position relative the window opening, and stop means on the side plate units adjacent the armature plates and engageable with the adjacent ends of the respective magnets to retain same slightly spaced from the armature plates whereby the magnets retain the sash in place until the magnets are removed.

4. A window construction of the character described comprising, a window casing, a stop extending around the window casing defining a window opening, a window sash having a frame bodily movable relative the window opening, inter-engageable seal means on the window sash and stop to form a weathertight seal therebetween, a plurality of spaced magnetic units secured to the window sash around the periphery thereof, mild steel plates supported in each magnetic unit in laterally spaced relation and defining opposite sides of through passages, armature plates fixed on the stop and positioned to be engaged by edges of the side plates at the ends of the passage when the window sash is in window opening closing position, and a plurality of permanent magnets one for each magnetic unit removably and slidably positioned in the passages of the respective magnetic units, and stops in the respective passages adjacent the end thereof toward the armature plates to prevent the magnets engaging the armature plates whereby the magnets and side plates provide an increased magnetic flux to firmly hold the window sash relative to the window casing.

5. A window construction of the character described comprising, a window casing, a stop extending around the window casing defining a window opening, a window sash having a frame bodily movable relative the window opening, a resilient seal strip fixed on the stop, means on the window sash engageable with the resilient seal strip to form a weathertight seal therewith, a plurality of magnetic units each including a pair of mild steel plates laterally spaced and defining opposite sides of through passages, non-magnetic members supporting the pairs of mild steel plates in spaced relation and securing same to the window sash with the through passages perpendicular to the stop, armature plates fixed on the stop and positioned to be engaged by end edges of the side plates when the window sash is in window opening closing position, and a plurality of permanent magnets one for each magnetic unit removably and slidably positioned in the passages of the respective magnetic units in sandwiched relation to the mild steel plates, and non-magnetic stops in the respective passages adjacent the end thereof toward the armature plates to limit movement of the magnets toward the armature plates whereby the magnets are slightly spaced therefrom.

6. A window construction of the character described comprising, a window casing, a stop extending around the window casing defining a window opening, a window sash having a frame bodily movable relative the window opening, a resilient seal strip fixed on the stop, means on the window sash engageable with the resilient seal strip to form a weathertight seal therewith, a plurality of magnetic units secured to the window sash at the periphery thereof, said magnetic units having a through passage perpendicular to the stop, mild steel plates laterally spaced and defining opposite sides of the respec-

tive passages, armature plates fixed on the stop and positioned to be engaged by end edges of the side plates when the window sash is in window opening closing position, and a plurality of permanent magnets one for each magnetic unit removably and slidably positioned in the passages of the respective magnetic units, and non-magnetic means in the respective passages adjacent the end thereof toward the armature plates to retain the magnets in spaced relation relative to the armature plates whereby the magnets and side plates provide an increased magnetic flux to firmly hold the window sash relative to the window casing.

7. A window construction of the character described comprising, a window casing, a blind stop extending around the casing defining a window opening, a window sash having a frame bodily movable through the window opening, means on the window casing pivotally mounting the window sash for movement of said sash from open position to window closing position, an auxiliary frame removably positioned in surrounding relation to the window sash and having portions for engaging the sash and casing to form a weathertight seal therewith, a plurality of permanent bar magnets, a plurality of armature plates fixed to the window casing around the window opening, a plurality of magnet housings each having a pair of laterally spaced mild steel plates forming sides of passages perpendicular to the armature plates whereby the magnets are removably and slidably positioned and sandwiched between the respective pairs of plates, means mounting the magnet housings on the auxiliary frame with the passages between the plates registering with the armature plates and the ends of the side plates engaging said armature plates when the auxiliary frame is in sealing engagement with the seal strips on the casing and sash, and stops in the passages between the side plates adjacent the end toward the armature plates and engageable with the end of the magnets to limit movement thereof toward the armature plates.

8. A window construction of the character described comprising, a window casing, a blind stop extending around the casing defining a window opening, a window sash having a frame bodily movable through the window opening, means on the window casing pivotally mounting the window sash for movement of said sash from open position to window closing position, a resilient seal strip on the casing blind stop around the window opening, an auxiliary frame removably positioned in surrounding relation to the window sash and having portions for engaging the seal strip on the casing to form a weathertight seal therewith, a plurality of permanent bar magnets, a plurality of armature plates fixed to the window casing around the window opening, a pair of laterally spaced mild steel plates for each magnet, non-magnetic members supporting the pairs of plates in spaced relation in units forming open ended housings with through passages between the pairs of side plates perpendicular to the armature plates whereby the magnets are removably and slidably positioned and sandwiched between the respective pairs of plates, means mounting the plate units on the auxiliary frame with the passages between the plates registering with the armature plates and the ends of the side plates engaging said armature plates when the auxiliary frame is in sealing engagement with the seal strips on the casing and sash, and non-magnetic means in the passages between the side plates of the respective side plate units adjacent the end toward the armature plates and engageable with the end of the magnets to retain same slightly spaced from the armature plates whereby the magnets retain the sash in place until the magnets are removed.

9. A window construction of the character described comprising, a window casing, a blind stop extending around the casing defining a window opening, a window sash having a frame bodily movable through the window opening, means on the window casing pivotally mounting

the window sash for movement of said sash from open position to window closing position, a resilient seal strip on the window sash, a second resilient seal strip on the casing blind stop around the window opening, an auxiliary frame removably positioned in surrounding relation to the window sash and having portions for engaging the seal strips on the sash and casing to form a weather-tight seal therewith, a plurality of permanent bar magnets, a plurality of armature plates fixed to the window casing around the window opening, a pair of laterally spaced mild steel plates for each magnet, non-magnetic members supporting the pairs of plates in spaced relation in units forming open ended housings with through passages between the pairs of side plates perpendicular to the armature plates, said passages between the side plates having a cross section substantially corresponding to the cross-sectional shape and size of the respective magnets whereby the magnets are removably and slidably positioned and sandwiched between the respective pairs of

5 plates, means mounting the plate units on the auxiliary frame with the passages between the plates registering with the armature plates and the ends of the side plates engaging said armature plates when the auxiliary frame is in sealing engagement with the seal strips on the casing and sash, and non-magnetic means in the passages between the side plates of the respective side plate units adjacent the end toward the armature plates and engageable with the end of the magnets to retain same slightly spaced from the armature plates whereby the magnets retain the sash in place until the magnets are removed.
